[57] CLAIM

The ornamental design for a fishing lure, substantially as shown.

DESCRIPTION

FIG. 1 is a side elevational view of a fishing lure showing my new design;

FIG. 2 is an end view thereof;

FIG. 3 is a plan view taken from the top thereof;

FIG. 4 is a side elevational view showing the side opposite that of FIG. 1;

FIG. 5 is a front view thereof; and

FIG. 6 is a plan view taken from the bottom thereof.
